UNITED STATES PATENT OFFICE

132,862

DESIGN FOR A TELEPHONE REMINDER

George E. Morton, Los Angeles, Calif.

Application November 4, 1941, Serial No. 104,017

Term of patent 14 years

To all whom it may concern:

Be it known that I, George E. Morton, a citizen of the United States, residing at Los Angeles, in the county of Los Angeles, State of California, have invented a new, original, and ornamental Design for a Telephone Reminder, of which the following is a specification, reference being had to the accompanying drawing, forming part thereof.

Fig. 1 is a perspective view of a telephone reminder embodying my new design, showing the ruled sliding member partially withdrawn from the frame;

Fig. 2 is a perspective view thereof with the ruled sliding member in position for use; and

Fig. 3 is a side elevational view of the telephone reminder shown in Fig. 2 on a larger scale.

I claim:

The ornamental design for a telephone reminder, as shown and described.

GEORGE E. MORTON.
